UNITED STATES PATENT OFFICE

108,756

DESIGN FOR A MEDICINE CABINET OR SIMILAR ARTICLE

Elmer J. Swanson, Chicago, Ill.

Application April 7, 1936, Serial No. 61,990

Term of patent 3½ years

To all whom it may concern:

Be it known that I, Elmer J. Swanson, a citizen of the United States, residing at Chicago, in the county of Cook and State of Illinois, have invented a new, original, and ornamental Design for a Medicine Cabinet or Similar Article, of which the following is a specification, reference being had to the accompanying drawing, forming a part thereof.

In the drawing:—

Figure 1 is a top plan view of the cabinet, showing my new design, the body of the cabinet being shown in dotted lines; and

Fig. 2 is a front elevational view thereof.

The essential features of my design reside in the configuration of the door of the cabinet shown in full lines, the door extending to substantially the height of the cabinet and having a recessed central panel connected by opposed beveled edges to the sides of the door with the panel extending vertically the length of the door, as shown.

I claim:

The ornamental design for a medicine cabinet or similar article substantially as shown and described.

ELMER J. SWANSON.
